(57) **CLAIM**

The ornamental design for a hearing prosthesis sleeve, as shown and described.

DESCRIPTION

FIG. 1 is a perspective view of the hearing prosthesis sleeve of the present design;

FIG. 2 is a front view thereof;

FIG. 3 is a rear view thereof;

FIG. 4 is a right side view thereof, the left side being a mirror image;

FIG. 5 is a top view thereof;

FIG. 6 is bottom view thereof; and,

FIG. 7 is a right side view thereof with a bottom plug in an open position.

The broken lines in the drawing views represent unclaimed portions of the hearing prosthesis sleeve and form no part of the claimed design.
